UNITED STATES PATENT OFFICE

161,667

MANICURIST'S HAND REST

Ernest H. Westmore, North Hollywood, Calif.

Application September 19, 1949, Serial No. 5,068

Term of patent 14 years

(Cl. D86—10)

To all whom it may concern:

Be it known that I, Ernest H. Westmore, a British subject, residing at North Hollywood, in the county of Los Angeles and State of California, have invented a new, original, and ornamental Design for a Manicurist's Hand Rest, of which the following is a specification, reference being had to the accompanying drawings, forming a part thereof.

Fig. 1 is a perspective view of the hand rest, showing my new design, taken to show the top or upper side thereof; Fig. 2 is a bottom plan view of the hand rest; Fig. 3 is a front end elevation of the hand rest; Fig. 4 is a rear end elevation of the hand rest; Fig. 5 is a side elevation of the hand rest taken from one side, and Fig. 6 is a side elevation of the hand rest taken from the other side thereof.

I claim:

The ornamental design for a manicurist's hand rest, as shown.

ERNEST H. WESTMORE.
